UNITED STATES PATENT AND TRADEMARK OFFICE
Certificate

Patent No. D539,155 S

Patented: March 27, 2007

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Tony Steinmann, Green Bay, WI (US); and Christopher W. Lussier, Milford, NH (US)

Signed and Sealed this Third Day of August 2010.
